CLAIM

(21) Appl. No.: **29/587,824**

The ornamental design for a faucet with handle, as shown and described.

(22) Filed: **Dec. 15, 2016**

DESCRIPTION

(51) **LOC (11) Cl.** **23-01**

FIG. 1 is a front perspective view of a faucet with handle showing my new design;

(52) **U.S. Cl.**

FIG. 2 is a right side view thereof;

USPC **D23/252**

FIG. 3 is a left side view thereof;

(58) **Field of Classification Search**

FIG. 4 is a front view thereof;

USPC D23/238–242, 249–250, 252, 254;
D8/307–308

FIG. 5 is a rear view thereof;

CPC E03C 1/0412; Y10T 137/9464

FIG. 6 is a top view thereof;

See application file for complete search history.

FIG. 7 is a bottom view thereof;

(56) **References Cited**

FIG. 8 is a front perspective view of the faucet with handle of FIGS. 1–7 with the handle shown in an alternative position;

U.S. PATENT DOCUMENTS

FIG. 9 is a right side view thereof;

D424,171 S * 5/2000 Fabian D23/238
D443,921 S * 6/2001 Tolosa D23/250
D717,400 S 11/2014 Hanna et al.
D723,661 S 3/2015 Zhang
D736,898 S 8/2015 Garland
D777,882 S * 1/2017 Hong D23/252

FIG. 10 is a left side view thereof;

FIG. 11 is a front view thereof;

FIG. 12 is a rear view thereof;

FIG. 13 is a top view thereof; and,

FIG. 14 is a bottom view thereof.

The uneven-length broken line surrounding the shaded area represents an unclaimed peripheral boundary of the design. The broken line showing of the ovals and the remainder of the faucet represents unclaimed subject matter and forms no part of the claimed design.
